Clemir J. Ney, of Lowell, Mass.

Assignor to

The Lowell Manufacturing Company,
Letters Patent No. 1646, dated Aug. 12, 1862.

The schedule referred to in these Letters Patent and making part of the same.

To all whom it may concern:

Be it known that I, Clemir J. Ney, of Lowell, in the County of Middlesex and State of Massachusetts, have originated and designed a new Pattern for Carpets or other fabrics, of which the following is a full, clear and exact description, reference being had to the accompanying drawings, making part of this specification.

This pattern consists of two series of small blocks, in groups of five each. The outside blocks of each group in one series, are connected with the corresponding blocks in the other series, by larger many sided blocks.

The spaces intervening, are occupied by dotted lines which, by their connections, form diamonds of various sizes.

The colors employed for the different portions of this design may be varied to suit the taste and wish of the manufacturer.

Claim.

What I claim as my invention, and desire to secure by Letters Patent, is the design or pattern for Carpets or other fabrics, herein set forth.
